RADIATOR CAP

Kyle E. Stant, Connersville, Ind.

Application March 19, 1930. Serial No. 436,948

7 Claims. (Cl. 220--40)

My invention relates to closure means.

It is a particular object of my invention to provide a closure for a tank filler pipe whether for water, gasoline, or the like, which will prevent the complete detachment and separation of the cap from the filler pipe hereinafter known as the filler spout at that portion particularly involved in this construction.

It is particularly my object to provide a filler spout having locking cams and stops and a holder associated therewith for preventing the complete detachment and separation of the closure cap from the spout after it has been removed therefrom.

15 It is a further object to provide a means of a permanent but flexible attachment between the spout and the closure cap, which can be telescopically arranged within the spout when the cap is in position, and which will be connected to an integral part of the spout that tends to direct the flexible connector into telescopic position.

20 It is an especial object to provide means of connection of the flexible connector to the closure cap which would cooperate in this telescopic arrangement when the parts are in closed position.

25 It is a further object of the invention to provide a sealing means between the closure cap and the filler spout, which will not be disturbed in its operation by the telescoping of the flexible connection between the filler spout and the cap.

Referring to the drawings:

30 Figure 1 is a side elevation of the parts in closed position;

Figure 2 is a section on the line 2--2 thereof showing the parts in open position;

Figure 3 is a bottom plan view of the closure cap;

40 Figure 4 is a top plan view of the filler spout;

Figure 5 is a section on the line 5--5 of Figure 1.

45 Referring to the drawings in detail, 1 is a closure cap having a marginal rim 2 within which is a depending lug 3, of which there are a series at spaced intervals for engaging the top of the spring plate 4 that is mounted in the slot 5 of the depending sleeve 6 centrally and interiorly arranged on the under side of the cap 1.

50 On either side of the inner portion of the plate 4 are gaskets 7 for sealing the juncture of the spring 4 and the depending member 6 and a gasket 8 for sealing the juncture of the spring plate 4 and the depending member 6 at its inner end and the juncture between the spring

plate 4 and the top 9 of the filler spout 10 on its outer rim.

Also carried on this depending member 6 is a downwardly and outwardly extending cup member 11 having a narrow outwardly directed locking finger 12 and a wide outwardly directed finger 12a. The rim of the cup is also provided with a depending ear 13 to which is attached one end of a chain 14 that acts as a flexible connector that may be telescopically arranged within the filler 65 spout 10 with the other end connected at 15 to the depending ear 16.

This ear 16 which projects an appreciable distance into the interior of the spout 10 is mounted on the inwardly turned cam flange 17 which has a cam face 18 for receiving the locking fingers 12 and 12a. The smaller finger 12 rides on the surface 18 and is inserted through the small opening 19 while the larger finger 12a is inserted through the larger opening 20. Thus, the filler 75 spout and cap are aligned with respect to one another so as to insure the proper positioning and telescoping of the flexible connector 14 and the proper positioning of the cap 1.

It is essential to observe that the locking cup 11 is mounted on the depending member 6 rigidly.

It should be further observed that the cap 1 is flexibly connected by the same means, namely, the cup 11, to the spout 10, which is also used for locking the cap to the spout. This common means is the cup 11 which carries the locking fingers 12 and 12a and the flexible connector 85 ear 13.

It will be understood that I desire to comprehend within my invention such modifications as may be necessary to adapt it to varying conditions and uses.

Having thus fully described my invention, what I claim as new and desire to secure by Letters Patent, is:—

1. In combination, a spout, a cap therefor having a locking cup, a rigid locking means on the spout, and means on the rigid locking means to carry one end of a flexible connector, the other end of said connector to be carried by the locking cup on the cap.

2. In combination, a spout having a locking means, a cap, a locking cup on said cap having an ear spaced from the center portion thereof, a flexible connector connected to said locking means and to the ear, and a sealing means carried by said cap adapted to engage the spout to close the opening of the spout when the cap is in locked position.

3. In combination, a cap having a depending

centrally arranged locking cup attached rigidly thereto with locking fingers thereon, a connector lug on the cap, a flexible sealing means between said cup and the cap, a filler spout, interiorly disposed locking cams thereon, a connector connected at one end to the connector lug and at the other end to the locking cam whereby the locking means of the cap is telescopically arranged in locking position with the flexible connector disposed within the spout.

4. In combination, a filler spout having a sealing edge and interiorly disposed locking cams, a flexible connector support interiorly disposed therein, one end of the connector being connected to the cam, a cap, a flexible closure supported thereby, a rigid locking means supported thereby, and means for connecting the other end of the flexible connector on said rigid locking means adjacent one side thereof.

5. In combination, a spout having inwardly turned and depending locking cam surfaces with unequal width slots therebetween, a finger depending therefrom, a flexible connector connected to the finger, a cap, a cup member on the cap, having rigidly mounted locking fingers thereon of unequal widths, a finger on the cup

member for supporting the flexible connector thereon whereby the cap when positioned on the spout will be aligned and locked upon rotation.

6. In combination, a spout having interior downwardly depending cam members, a cap for said spout, a locking member carried by said cap for cooperatively engaging said cam members, a sealing means arranged between the cap and the locking member, a depending lug on said locking member, a flexible connector one end of which is attached to a cam member and the other end to the lug, whereby said lug enters the spout adjacent the cam members during application of the cap to the spout.

7. In combination, a spout having an inturned cam, a lug depending from said cam, a closure cap for said spout, a sealing means carried by said cap, a locking member carried by said cap for cooperatively engaging said cam, a lug depending from said locking member spaced from the center thereof, a single flexible member attached to each of the two lugs, whereby the flexible member is disposed interior the spout when said cap is in locked position on said spout.
